UNITED STATES PATENT OFFICE

170,363

SPINET PIANO OR SIMILAR ARTICLE

Joseph Palma, Jr., Chicago, Ill., assignor to Story
& Clark Piano Company, Chicago, Ill., a corpora-
tion of Delaware

Application October 29, 1952, Serial No. 22,032

Term of patent 14 years

(Cl. D56—9)

To all whom it may concern:

Be it known that I, Joseph Palma, Jr., a citizen of the United States of America, residing in Chicago, Illinois, have invented a certain new, original, and ornamental Design for a Spinet Piano or Similar Article, of which the following is a specification, reference being had to the accompanying drawing, forming a part hereof.

Fig. 1 is a perspective view of a spinet piano or similar article showing my new design.

Fig. 2 is a top plan view thereof.

Fig. 3 is a side perspective view thereof.

I claim:

The ornamental design for a spinet piano or similar article, substantially as shown.

JOSEPH PALMA, JR.
